US00D974342S

(12) **United States Design Patent** (10) **Patent No.:** **US D974,342 S**
(45) **Date of Patent:** **** Jan. 3, 2023**

(54) **ELECTRONIC DEVICE**

(71) Applicant: **Samsung Electronics Co., Ltd.**, Suwon-si (KR)

(72) Inventors: **Ji-Young Lee**, Suwon-si (KR); **Hyok-Su Choi**, Suwon-si (KR); **Chung-Ha Kim**, Suwon-si (KR); **Jong-Bo Jung**, Suwon-si (KR); **Min-Young Park**, Suwon-si (KR)

(73) Assignee: **SAMSUNG ELECTRONICS CO., LTD.**, Suwon-si (KR)

(**) Term: **15 Years**

(21) Appl. No.: **29/729,153**

(22) Filed: **Mar. 24, 2020**

(30) **Foreign Application Priority Data**

Sep. 26, 2019 (KR) 30-2019-0046172

(51) **LOC (14) Cl.** **14-03**

(52) **U.S. Cl.**

USPC **D14/248**

(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines in the figures illustrate portions of the electronic device that form no part of the claimed design. The dot-dash broken lines in the figures define the boundaries of the claimed design and form no part thereof.

1 Claim, 8 Drawing Sheets
